UNITED STATES PATENT OFFICE

108,601

DESIGN FOR A COAT

Henry Miller, New York, N. Y.

Application December 22, 1937, Serial No. 73,790

Term of patent 3½ years

To all whom it may concern:

Be it known that I, Henry Miller, a citizen of the United States, residing at 7 West 96th Street, in the county of New York, and city and State of New York, have invented a new, original, and ornamental Design for a Coat, of which the following is a specification, reference being had to the accompanying drawing constituting a part thereof.

Fig. 1 is a front view of the coat.

Fig. 2 is the rear view of the coat as shown in Fig. 1.

The characteristic features of the coat resides in the stitching of the back in arcs, the vertical stitched pockets and the V-shaped flaps of the cuffs.

I claim:

The ornamental design for a coat substantially as shown and described.

HENRY MILLER.
